UNITED STATES PATENT OFFICE.

HENRY W. PLEISTER, OF WESTFIELD, NEW JERSEY, ASSIGNOR TO HENRY B. NEWHALL;
HENRY B. NEWHALL, JR., EXECUTOR OF SAID HENRY B. NEWHALL, DECEASED.

GUY-CLAMP.

1,287,742.

Specification of Letters Patent. Patented Dec. 17, 1918.

Application filed May 18, 1917. Serial No. 169,601.

To all whom it may concern:

Be it known that I, HENRY W. PLEISTER, a citizen of the United States, residing at Westfield, in the county of Union and State 5 of New Jersey, have invented certain new and useful Improvements in Guy-Clamps, of which the following is a specification, taken in connection with the accompanying drawing.

10 My invention relates to guy clamps and more particularly to such guy clamps as are used in telephone and telegraph installations. The advantages of my invention will be more fully hereinafter pointed out in the 15 specification and claims.

In the accompanying drawing, in which the same reference numerals refer to the similar parts in the several figures—

Figure 1 is a plan view of my guy clamp 20 showing the messenger located in the guy clamp and broken away;

Fig. 2 is a longitudinal, vertical section substantially on the line 2—2 of Fig. 1;

Fig. 3 is a longitudinal, vertical section 25 substantially on the line 3—3 of Fig. 1;

Fig. 4 is a transverse, vertical section on the line 4—4 of Fig. 3; and

Fig. 5 is a diagrammatic view of the wave line in the grooves of the guy clamp.

30 The common practice of running messenger strands between poles, up to a comparatively recent date, was to take the end which would not reach to the next pole, known among the linemen as the "dead end", and wrap it around the last pole reached. This caused a loss of from approximately ten to one hundred feet of most expensive wire 35 messenger strand.

In the new practice the messenger strand 40 is continued without wrapping or other interruption by means of connections should the end of messenger strand not extend to the next pole. The free end of the messenger strand is bent back on itself forming 45 an eye (not shown) which engages the end of the next stretch of messenger.

The end of the messenger which is bent back is secured by means of several guy clamps to obtain the necessary holding capacity. The slipping of the guy clamps is 50 very dangerous for the reason that it may occur when a lineman is in a boatswain's seat between poles causing loss of life. Or if the guy clamp is used to brace a pole the 55 guy clamp might slip when the pole is under

heavy wind or sleet pressure permitting the pole and wires to fall. For these reasons a plurality of ordinary guy clamps have to be used for each connection which necessitates an additional outlay and additional 60 labor in installing them.

Ordinarily two, three or more standard guy clamps are used on each interlocking end of the strand. These clamps are comparatively expensive and it takes time and 65 labor to properly position them. The total holding capacity of these guy clamps is the combined compression obtained by the bolts in each of the separate guy clamps.

By my invention I make one guy clamp 70 of substantially the same length of an ordinary guy clamp, do the work of two such guy clamps. I have shown, for example, in my drawings a guy clamp 1 formed of the duplicate members 2 and 3. The member 2 75 is provided with two or more unthreaded bosses 4, 5 and 6. Between these unthreaded bosses 4, 5 and 6, I mounted threaded bosses 7, 8 and 9. The member 3 is provided with two or more unthreaded bosses 14 and 15. 80 Alternating with these unthreaded bosses I mount threaded bosses 10, 12 and 13.

The two members 2 and 3 are identical and by reversing them end to end a threaded boss will position itself opposite each unthreaded boss of the opposite member. 85

In the coöperating bosses are mounted the sets of bolts 16, 16. It will be noted that the threaded bosses come between the heads 17 of the bolts 16. This insures that sufficient 90 space will be left between the different heads 17, 17 of the bolts 16, 16 to permit a very large wrench to be used, such as commonly used by linemen in the field.

The average pressure on each bolt, which 95 is required under service conditions, is approximately 16,000 pounds tensile strength. It is, therefore, obvious that a very large wrench is required to coöperate with the heads 17, 17 of the bolts. The bolt ordinarily used for this heavy work is a $\frac{5}{8}$ " bolt. Of course, where a larger bolt is used greater pressure than 16,000 pounds would be developed by each bolt, while a lighter bolt 100 would not exert less tensile strength.

105 It will be noted that the screwthreaded bosses, not only space the bolts from each other, but also avoid the use of nuts which would lie between the bolt heads and prevent the proper manipulation of the wrench. The 110

use of nuts would also entail additional labor in assembling and additional expense of material.

It will also be noted that the bolt heads 5 17 lie on opposite sides of the guy clamp, so that in a clamp using six bolts, such as that shown, three of the heads 17 can be easily operated from one side of the guy clamp with a large wrench, while the remaining three can be operated by the same wrench from the other side.

If it were attempted to simply lengthen 15 one of the ordinary guy clamps and obtain therein essentially the same grip as I obtain in my guy clamp, the length of the members 2 and 3 would have to be at least double the length of the present clamp, which is now in use. This would accordingly double the weight and cost of the clamp, besides placing an additional and unnecessary load on the messenger. This is 20 due to the fact that the heads of the bolts must be spaced far enough apart to permit manipulation by the large wrench required 25 for this work.

In my guy clamp I locate six bolts in practically the same length guy clamp as is now used for three bolts, and thereby save cost of material, and, further, obtain a clamp 30 having the same holding capacity as two ordinary standard guy clamps. The increased holding capacity is due to the combined compression of the same number of bolts ordinarily used in two clamps, making it equivalent in holding capacity to two 35 regular clamps which would ordinarily occupy at least twice the space, and require additional labor, in mounting them. Obtaining a short powerful guy clamp is also of 40 great value for the dead end of the messenger 18 is often short.

Each of the members 2 and 3 is provided 45 with grooves 19, 19 which have a wave line so that there are no rights or lefts in the members 2 and 3, thus reducing the cost of the pattern equipment, the number of different parts to be made for assembling the clamp, and a corresponding reduction in the cost of stock to be carried in order to 50 turn the clamps out.

I have shown diagrammatically in Fig. 5, such a wave line which is in the cable grooves 19, 19. The neutral point is 20 and is in the center of the clamp 1. It is ob-

vious that with such a wave line my clamp has no rights or lefts. This insures that the number of parts necessary for assembling one of my guy clamps is reduced for both sides are identical.

While I have shown six bolts, three on 60 a side, it is of course to be understood that any desired number of bolts may be used. Thus for example, I could use three bolts and make a clamp of equal holding capacity in half the length of the present form of 65 three bolt clamp.

Having thus described this invention in connection with an illustrative embodiment thereof, to the details of which I do not desire to be limited, what is claimed as new 70 and what is desired to secure by Letters Patent is set forth in the appended claims.

What I claim as my invention and desire to secure by Letters Patent is:—

1. A guy clamp formed of two clamping 75 members having alternate threaded and unthreaded bosses and bolts to coöperate with the bosses.

2. A guy clamp formed of two duplicate clamping members having alternate threaded 80 and unthreaded bosses thereby avoiding rights and lefts, and bolts to coöperate with the bosses.

3. A guy clamp formed of two clamping 85 members having alternate threaded and unthreaded bosses, the threaded bosses acting as spacers between the heads of the bolts to permit their manipulation and bolts to co-operate with the bosses.

4. A guy clamp composed of two duplicate members provided with alternating threaded and unthreaded bosses so placed 90 that when reversed end to end and placed one upon the other each threaded boss will lie axially opposite an unthreaded boss. 95

5. A guy clamp composed of two duplicate members provided with alternating threaded and unthreaded bosses so placed that when reversed end to end and placed one upon the other each threaded boss will 100 lie axially opposite an unthreaded boss, the unthreaded bosses being elevated above the threaded bosses to permit clearance between bolt heads for a wrench.

HENRY W. PLEISTER.
